(57) **CLAIM**

The ornamental design for a disposable wild bird feeder, as shown and described.

DESCRIPTION

FIG. 1 is a perspective view of a disposable wild bird feeder showing my new design;

FIG. 2 is a front elevation view of the disposable wild bird feeder of FIG. 1, the opposite side being a mirror image;

FIG. 3 is a left side elevation view of the disposable wild bird feeder of FIG. 1;

FIG. 4 is a top view of the disposable wild bird feeder of FIG. 1;

FIG. 5 is a bottom view of the disposable wild bird feeder of FIG. 1;

FIG. 6 is a sectional view of the disposable wild bird feeder of FIG. 1 taken along line 6—6 in FIG. 4;

FIG. 7 is a sectional view of the disposable wild bird feeder of FIG. 1 in a shipping and storage configuration prior to use;

FIG. 8 is a sectional elevation view of a top portion of the disposable wild bird feeder of FIG. 1;

FIG. 9 is a perspective view of a bottom portion of the disposable wild bird feeder of FIG. 1 that is unreleasably coupled with the top portion of FIG. 8; and,

FIG. 10 is a plan view of one perch of a plurality of perches rotatably attached to the bottom portion of FIG. 9 to support feeding birds of the disposable wild bird feeder of FIG. 1.

The stippling of FIGS. 6 and 7, indicating the extent of feeding material in the disposable wild bird feeder, is for illustrative purposes only and forms no part of the claimed invention.
